TRAFFIC LANE DIVIDER

Bernard N. Landeen, Chicago Heights, Ill., assignor to The Translode Joint Company, Chicago Heights, Ill., a corporation of Illinois

Application March 4, 1937, Serial No. 128,891

9 Claims. (Cl. 94—1.5)

This invention relates to improvements in traffic lane dividers for use on concrete roads for dividing the road into a series of traffic lanes, said improved traffic lane dividers consisting of rail sections positioned in abutting relation end to end and having upwardly projecting waved ribs integrally formed a part thereof to provide tapered grooves on opposite sides of the traffic lane divider rails to assist in directing vehicles striking the divider back onto the pavement.

It is an object of this invention to provide a traffic lane divider wherein the same is formed by means of placing rail members end to end so that rail members formed on the rail members will be positioned to connect up with one another and form a continuous waved rib forming staggered or diagonally opposite tapered recesses on opposite sides of the traffic lane divider to prevent binding of the wheels of a vehicle striking the divider and also serving to assist in directing the vehicle away from the divider into a proper position in a traffic lane.

Another object of the invention is to provide a road traffic lane divider formed of a plurality of abutting rail members having directional ribs integrally formed thereon in such a manner that when the rail members are positioned upon a road the ribs will form a continuous wave formation producing tapered pockets on opposite sides of the divider for obviating binding of vehicle wheels against the sides of the divider and tending to direct the vehicle back onto its proper lane rather than permitting the vehicle to cross over the divider into an adjacent lane.

It is a further object of this invention to provide an improved traffic lane divider made up of a plurality of standard rail sections adapted to be placed end to end in alternating relation to produce a continuous waved rib along the top of the divider with said rib being provided at spaced intervals with sparkler means to permit the traffic lane divider to be readily discernible at night.

It is an important object of this invention to provide an improved traffic lane divider for use on roads. Said traffic lane divider being constructed of rail sections having rail members of various configurations integrally formed on the top thereof so that when the rail sections are placed in a selected aligned order on a road they will produce a continuous waved rib producing alternately arranged tapered pockets or recesses on opposite sides of the divider serving to obviate binding of vehicle wheels against the side of the divider and furthermore acting to assist the ve-

hicle in being directed away from the side of the traffic lane divider, thereby obviating the promiscuous or accidental crossing of vehicles from one traffic lane over a traffic lane divider into an adjacent traffic lane.

Other and further important objects of this invention will be apparent from the disclosures in the specification and the accompanying drawing.

The invention, (in preferred form) is illustrated in the drawing and hereinafter more fully described.

On the drawing:

Figure 1 is a fragmentary top plan view of a road having mounted longitudinally thereon an improved traffic lane divider embodying the principles of this invention, and separating the road into traffic lanes.

Figure 2 is a fragmentary side elevational view of the structure illustrated in Figure 1.

Figure 3 is an enlarged top plan view of one form of traffic lane divider rail section having sparklers supported on an inclined rib member.

Figure 4 is a side elevation of the divider rail section illustrated in Figure 3.

Figure 5 is a transverse detail section of the rail section taken on line V—V of Figure 3 and illustrating the retainer bolt in elevation.

Figure 6 is a fragmentary top plan view of a portion of the traffic lane divider illustrating a second form of rail section having an S-shaped rib integrally formed thereon with the ends of said S-shaped rib registering with the ends of inclined ribs formed on rail sections of the type illustrated in Figure 3.

Figure 7 is a side elevation of the section of the traffic lane divider illustrated in Figure 6.

Figure 8 is an enlarged end view of the traffic lane divider rail section illustrated in Figure 3.

Figure 9 is an end elevation of a modified form of traffic lane divider rail section which may be used in place of the rail section shown in Figure 8.

As shown on the drawing:

This invention has as its object the providing of an arrangement for dividing the surface of a road or highway into separated traffic lanes by means of an improved traffic lane divider which is so constructed that when vehicles moving in opposite directions in adjacent lanes happen to be accidentally steered into the traffic lane divider, said vehicles will be directed away from one another back into their proper positions in their respective traffic lanes, thus avoiding accidents.

Figures 1 to 8 inclusive illustrate a preferred form of the traffic lane divider embodying the principles of this invention. The assembled traf-

fic lane divider illustrated in Figures 1 and 2 in its assembled form, is mounted longitudinally upon a concrete road to separate the concrete traffic lanes 1 and 2 from another. The improved traffic 5 lane divider is constructed of a plurality of metal rail sections 3 and 4 which are positioned end to end in abutting relation, in alternating relation with respect to one another, to form a substantially continuous traffic lane divider between the 10 two road lanes 1 and 2.

In the construction shown the metal rail sections 3 are longer than the rail sections 4. It will, of course, be understood that the length of the rail sections 3 and 4 may be varied depending 15 upon circumstances.

As clearly illustrated in Figures 3, 4 and 5, each of the divider rail sections 3 has integrally formed upon the top thereof a diagonally disposed deflecting rib 5, the top of which is rounded as at 6. 20 Each side of the diagonal rib 5 is of a concave construction starting out at one end of the rail section with the large curve 7, illustrated in Figure 8, and gradually tapering toward the opposite end of the rail section upwardly and outwardly to provide a guide pocket or groove 8. 25 As clearly illustrated in Figure 3, the two side grooves or pockets 8 on opposite sides of the rib 5 of the rail sections 3 are tapered in opposite directions with respect to one another. The rib 30 portion of each of the divider rail sections 3 is provided with vertical openings or passages for the reception of anchoring bolts 9 adapted to securely anchor or hold the rail section 3 secure to the concrete forming the road. The anchoring 35 bolts 9 have sparkler buttons 10 formed on the heads thereof to afford a means for readily indicating the position of the divider rail sections at night.

Alternately arranged between the divider rail 40 sections 3 and abutting against the ends thereof are the shorter rail sections 4 which are also constructed out of metal. Each of the rail sections 4 has integrally formed on the top thereof an irregularly shaped or S-rib 11 the top of 45 which is curved or round complementary to the curvature 6 of the rib 5. The side walls of the S-shaped rib 11 curves downwardly and outwardly toward the sides of the rail section 4 and form rounded or concave pockets or grooves 50 which are disposed diagonally opposite one another on opposite sides of the dividing rib 11. The pockets or grooves formed on the opposite sides of the rib 11 are indicated by the reference numeral 12 and are so shaped that the ends 55 thereof are of the same size and register with the ends of the pockets or recesses 8 on opposite sides of the ribs 5 of the rail sections 3. As clearly illustrated in Figure 6, the pockets 12 and 8 coact with one another to provide alternately 60 staggered rounded and tapered grooves on opposite sides of the continuous divider rib formed by the coacting relationship of the ribs 6 and 11 of the aligned divider rail sections 3 and 4. The rib portions 11 of each of the rail sections 4 are 65 provided with vertical openings or passages for the reception of retaining bolts 9 for holding the rail sections 4 anchored to the concrete.

As clearly illustrated in Figures 2 and 7, the 70 aligned rail sections 3 and 4 have the concave tapered pockets or grooves 8-12 formed in staggered relation on opposite sides of the continuous ribs 5-11, provides a traffic lane divider having side walls 13 of graduated height to form walls having wave-shaped crests with the low points 75 of the walls 13 registering with the low portions

of the side pockets or grooves 12 to permit the wheels of a vehicle when directed against the traffic lane divider to engage in one of the rounded and tapered side grooves of the divider permitting the inclined ribs to guide the vehicle back into the lane from which it came. As the wheel of a vehicle is directed into one of the side grooves, it runs upwardly on the inclined surface of the groove toward the tapered end thereof and as said tapered end of the groove 8 is narrowed 10 toward the end of a rail section the tire of the wheel reaches the high point of the side wall 13 and slips off of the side of the divider back onto the concrete pavement.

Figure 9 illustrates a modified form of traffic 15 lane divider rail section 14 constructed of iron or steel or any suitable material and having formed integrally thereon a diagonally positioned rib 15 having a rounded top 16. The rib portion 20 of the rail section is provided with vertical side walls 17 which are higher at one end of the rail section and tapered toward the other end of the rail section. The lower upwardly inclined edge 25 of each of the side walls 17 of the rib 15 registers with an inclined tapered surface 18, the lower end of which is wider than the upper end. This construction provides for angularly tapered pockets or grooves on opposite sides of the rib 15.

In a similar manner, an intermediate rail section corresponding with the rail section 4 may be 30 provided for use with the rail section 14. The intermediate rail section is provided with diagonally opposite angular pockets or grooves on opposite sides of a diagonally disposed rib to provide an arrangement substantially the same as 35 that illustrated in Figure 6 except, that the diagonally opposite pockets for diverting the wheels of a vehicle outwardly, are of angular shape instead of being rounded or concave.

The improved traffic lane divider of this invention is adapted to separate the traffic between adjacent lanes of a road or highway to prevent the promiscuous driving of vehicles from one lane into an adjacent lane. The improved type of traffic lane divider herein described is constructed with the waved rib thereof having alternate sections thereof disposed diagonally across the top of the divider in such a manner that tapered concave recesses or pockets are formed on diagonally opposite sides of the rib portion to afford an arrangement whereby the wheels at 45 one side of a vehicle, which may be accidentally directed against the side of the traffic lane divider, are prevented from binding with the side of the divider for the reason that the tires of the wheels are adapted to engage in any one of the pockets 12-8, so that the wheel engaged in said pocket, is caused to run upwardly and outwardly away from the rib until the crest of the side wall is reached when the wheel will slip off 50 of the side of the traffic lane divider back onto the concrete pavement of the lane in which the vehicle was normally driven. It will also be noted that if vehicles coming from opposite directions, in adjacent lanes of the road, happen to strike opposite sides of the traffic lane divider at substantially the same location that the two vehicles instead of colliding with one another will be directed outwardly away from one another by the shape of the waved rib and the tapered pockets 55 in the sides of the traffic lane divider, so that an accident is thereby avoided.

It will, of course, be understood that various details of construction may be varied through a wide range without departing from the principles 75

of this invention, and it is therefore, not the purpose to limit the patent granted hereon otherwise than necessitated by the scope of the appended claims.

5 5. I claim as my invention:

1. A road traffic lane divider comprising a plurality of long and short rail sections placed end to end in abutting relation, ribs integrally formed diagonally on the top of the long rail sections, 10

10 S-shaped ribs integrally formed upon the tops of the shorter rail sections and registering with the diagonal ribs on the long rail sections to form a continuous waved rib upon the top of the traffic lane divider and forming grooves of decreasing 15 depth on opposite sides of the continuous waved rib to enable a vehicle striking the side of the divider to be directed back to the proper side of the road.

15 2. A road traffic lane divider comprising a plurality of alternating long and short rail sections placed end to end in abutting relation, ribs integrally formed diagonally on the top of the long rail section, S-shaped ribs integrally formed upon the top of the shorter rail sections and registering with the straight diagonal ribs on the long rail sections to form a continuous waved rib upon the top of the traffic lane divider and providing 20 tapered grooves for enabling a vehicle to return to the proper side of the road, means for anchoring the rail sections in position to hold same aligned with respect to one another, and sparklers on the retaining means for making the traffic lane divider readily discernible at night.

25 3. A road traffic lane divider comprising a plurality of rail sections disposed end to end and having abutting alternately arranged diagonal and S-shaped rib members integrally formed on the tops thereof and forming reversed longitudinally tapered grooves decreasing in depth in the direction of traffic on the traffic lane and positioned on opposite sides of the rib members, said rib members having the ends thereof registering with the adjacent ends of adjoining rib members to form a continuous waved rib longitudinally of the traffic lane divider to enable a 30 vehicle striking in the enlarged deep end of one of the tapered grooves to follow along the line of decreasing depth of the groove to be returned to the proper side of the road from which it came.

35 4. A road traffic lane divider comprising a plurality of rail sections positioned end to end, diagonal and S-shaped rib members integrally formed on the tops of the rail sections and having diagonally opposite tapered grooves of decreasing depth in the direction of traffic and positioned on opposite sides of the rail sections, said rail sections arranged with alternate sections having the S-shaped rib members thereof outwardly directed with respect to the traffic lane and the diagonal rib members inwardly directed with respect to the traffic lane with the rib members of one rail section abutting and registering with the ends of the rib members of adjacent rail sections to form a continuous wave-like rib along the top of the traffic lane divider and with the 40 grooves of adjacent rail sections registering and forming staggered tapered recesses on opposite sides of the waved rib to cause a vehicle striking in one of the recesses to be returned to the side of the road from which it came.

45 70 5. A road traffic lane divider comprising an elongated base, a waved rib formed of abutting

alternately arranged S-sections outwardly directed with respect to the traffic lane and diagonal sections inwardly directed with respect to the traffic lane, said sections integrally formed on the top of the base and providing staggered 5 tapered recesses on opposite sides of the divider, with said recesses decreasing in depth in the direction of traffic on the traffic lane to enable a vehicle striking the divider in one of the recesses to be directed back onto the traffic lane from 10 which it came.

6. A road traffic lane divider comprising a body portion having parallel side walls, the upper edges of which are formed to provide alternating crests and depressions, and a waved rib integrally formed on the top of the body portion by S-shaped rib members outwardly directed with respect to the traffic lane and by diagonal rib members inwardly directed with respect to the traffic lane and providing tapered grooves on opposite sides of the divider with said grooves decreasing in depth in the direction of traffic on the traffic lane and opening through the side walls of the divider to form the alternating crests and depressions in said side walls to enable a 20 vehicle striking one side of the divider to return to the same side of the road.

7. A traffic lane divider comprising a body portion having diagonally opposite portions cut away from opposite sides thereof to form a waved 30 rib, including alternately arranged S-shaped sections directed outwardly with respect to the traffic lane and abutting diagonal sections inwardly directed with respect to the traffic lane, the bight portions of said rib alternately registering with the opposite side walls of the body portion of the divider and providing grooves of decreasing depth in the direction of traffic on the traffic lane to enable a vehicle engaging a groove to be directed away from the divider.

35 8. A road traffic lane divider comprising an elongated body portion having parallel side walls, said body portion having diagonally opposite tapered grooves formed therein decreasing in depth in the direction of traffic on the traffic lane and opening through the walls of the body portion forming a waved rib longitudinally of the body portion and separating the tapered grooves on each side of the divider from one another and from the tapered grooves on the opposite side of the divider to enable a vehicle striking one side of the divider to enter a tapered groove and be directed back to the same side of the road from which the approach was made.

40 9. A road traffic lane divider comprising a plurality of aligned rail sections positioned in abutting relation with respect to one another, alternately arranged diagonal and S-shaped rib sections integrally formed on the top of the rail sections with the ends of the diagonal rib sections of one rail section registering with the adjacent ends of the S-shaped rib sections on adjacent rail sections to form a continuous waved rib upon the top of the traffic lane divider providing staggered tapered guide grooves in the sides of the traffic 45 lane divider to enable a vehicle striking the divider to be returned to the proper side of the road, means for anchoring the traffic lane divider on the road, and means on the waved rib to indicate the location of the traffic lane divider on a 50 road at night.

BERNARD N. LANDEEN.
